Primary Examiner—James Gandy*Assistant Examiner*—Stacia Sinuik*Attorney, Agent, or Firm*—Jean H. Dubuc**[57]****CLAIM**

The ornamental design for a segment of a snowmobile track, as shown and described.

DESCRIPTION

FIG. 1 is a top plan view of a segment of a snowmobile track showing my new design;

FIG. 2 is a cross-sectional view taken along lines 2—2 of FIG. 1; and,

FIG. 3 is a side elevation view thereof.

The broken lines in FIGS. 2 and 3 are downwardly projecting elements not forming part of the claimed design.
